REHEATING METHOD AND FURNACE

Heinz Puppe, Neunkirchen Saar, Germany

Application October 6, 1936, Serial No. 104,285
In Germany October 11, 1935

1 Claim. (Cl. 80—60)

This invention relates firstly to an improved reheating method for the manufacture of long rolled profiled pieces of any desired sectional shape, for instance such as bars, wires, and the like, and secondly to an improved reheating furnace for carrying out that method.

When rolling bars, billets and profiled pieces of any kind the rolling material gradually cools down so that reheating in a rolling mill furnace to the proper rolling temperature is required if billets of large sectional area are to be rolled down, for instance to rods or wires of small sectional area. Particularly long pieces do not cool down uniformly along their entire length, but the front portion, i. e. the end to be rolled first as a rule cools down less than the other or rear portion. When rolling wire, for instance, the front end of the roughened billet, leaving the furnace with a uniform temperature along its entire length, is passed to and fro mechanically through the roughing train of rolls in quick succession, whereas the end of the wire due to the continuous decrease in diameter reaches the passes in increasing periods of time. Consequently considerably much more time for cooling down is given to this rear end of the wire than to the front end. The difference between the temperatures at the commencement of the rolling procedure and on leaving the last pass may amount to 150° C. even to 200° C. Naturally due to the temperature differences the rolling of the hotter front end of the material is carried out under conditions fundamentally different from those of the cooler rear portions which, with most kinds of steel, is accompanied by detrimental consequences as to strength, hardenability and the like.

The object of the present invention is to obviate the above-mentioned drawbacks in a simple manner and with simple means, and I attain the object in view by heating the material during the intermediate heating which takes place prior to the finish rolling to such a higher temperature at those portions which cool down quicker during the finish rolling that in the finish pass the material is of substantial uniform temperature along its entire length.

Hitherto attention has been paid solely to heating the material to be rolled as uniformly as possible in the reheating furnace. In contradistinction thereto in the method according to the invention, the rear end portions of billets are, if such billets are to be rolled to wires, heated more strongly than the front portions or heads of the same which are first introduced into the rolling mill passes.

This non-uniform heating can be carried out in a simple manner in a gas-fired furnace, as well as in an electrically heated one. In the first-mentioned type of furnaces, or in equivalent furnaces fired with liquid or solid fuel, rows of regulable burners are provided in the longitudinal direction of the material to be heated, say billets etc. whereas in the case of electric furnaces rows of resistances are provided which can be differently loaded.

The differences of temperature to be brought about in the furnace between the several zones, extending at right angles with respect to the longitudinal direction of the billets etc. to be conveyed through the furnace, must be regulated in accordance with the particular kind of the rolling procedure, because they depend on the rolling speed, the number of the passes, the reduction of the sectional area, the length of the billet and the finished profile respectively, as well as the local conditions and the outer temperature. The regulation can easily be effected by observing the temperatures of the individual longitudinal portions of a rolled profile, wire or the like on leaving the finishing groove. The observer may then regulate the differences of temperature between the various zones in the reheating furnace by remote adjustment of the burners or of the resistances until the finished profile is of uniform temperature along its entire length. Automatically operating devices may, however, also be used for regulating the burners or the resistances. Thus, for instance, photo-cells, pyrometers or the like, influencing the control members of the heating devices, may be employed through which the rolled pieces are conducted at the last pass.

The use of the above-described method ensures a uniform temperature of the rolled piece along its entire length, resulting in obtaining a uniform quality, strength, and grade of hardening.

The method according to the invention can be carried out, for instance, with the aid of the furnace illustrated diagrammatically and by way of example in the accompanying drawing which shows in perspective a transverse section through the furnace the rear portion of which being omitted.

In this drawing, 2 denotes a lateral aperture in the furnace wall through which the reheated pieces 3 (shown as bars in this case) are conveyed in the direction of the arrow to the rolling mill (not shown) by suitable means (likewise not shown). The bars 3 are supported side by side

by longitudinal bars 4 constituting in their entirety a sort of grate, extending over the entire length of the furnace.

Arranged in the longitudinal direction of the furnace below and above the grate 4 respectively are burners 5, 6, 7, 8, 9 and 10 and 11, 12, 13, 14, 15 and 16 respectively which extend vertically to the longitudinal axis of the material to be heated. Nozzles 17 and 18 respectively directing the flames against the bars 3 from below and from above project from the burners 5—11 and 11—16 respectively. Each of the burners is provided with a plurality of nozzles arranged in a definite distance from each other. The burners, extending all over the length of the furnace, may be supplied with gas, liquid or solid fuel and each of them is provided with a throttle valve 19 or the like which independently may be adjusted by means of rods 20. As mentioned already, the adjustment may be effected manually by remote control or automatically by means of photo-cells, pyrometers or the like in such a manner, that the amount of heat supplied to the bars 3 by the burners 5—10 and 11—16 increases in the direction from the burners 5, 11 to the burners 10, 16. By this arrangement, the ends

of the bars 3, which during rolling cool down quicker, are correspondingly more highly heated, resulting in obtaining uniform temperature of all parts of the material travelling through the last pass.

What I claim is:

In a method of manufacturing long profiled pieces of relatively rigid material such as rods, wires and the like, the steps of heating a bar of said material to rolling temperature; subjecting the bar to preliminary rolling operations; delivering said bar to a reheating furnace; simultaneously and independently reheating a series of substantially contiguous sections along the entire length of said bar while maintaining it against longitudinal movement in said furnace during said reheating and while regulating the temperatures of said sections and maintaining said temperatures at such levels that the trailing portion of said bar is heated to an appreciably higher temperature than the leading portion with a progressive temperature gradient between said portions; and then subjecting the reheated bar to further and finishing rolling operations.

HEINZ PUPPE.
